UNITED STATES PATENT OFFICE

1,984,756

TUBE HANDLING APPARATUS

John W. Offutt, Ellwood City, Pa., assignor to
 National Tube Company, a corporation of New
 Jersey

Application December 29, 1933, Serial No. 704,569

4 Claims. (Cl. 205—3)

This invention relates to a tube handling apparatus, and more particularly to an apparatus for the handling of tubes at a draw-bench prior to a cold drawing operation.

One object of the present invention is the provision of a novel tube handling apparatus such as will enable tubes to be more quickly positioned over mandrels and mandrel rods prior to their being processed.

This and other objects will be apparent after referring to the drawings, in which:

Figure 1 is a plan of the novel apparatus of the invention.

Figure 2 is a side elevation thereof.

Figure 3 is an end elevation of part of the apparatus.

Figure 4 is a side elevation of the apparatus of Figure 3.

Figure 5 is a plan of a modified form of the invention.

Figure 6 is a side elevation of the modification of Figure 5.

Figure 7 is an end view on the line VII—VII of Figure 2.

Referring more particularly to the drawings, the numeral 2 designates a conventional tube drawing bench having the usual head 3 in which various dies are placed for tube drawing operations. A support 4 at one end of the tube drawing bench 2 is adapted to support a mandrel rod 5 in such manner as to enable it to be moved laterally, but to restrict its forward longitudinal movement.

A mandrel 6 is positioned on the free end of the mandrel 5 for assuming a position immediately in the pass of a suitable die in the head 3.

The usual draw chain 7 is mounted adjacent the die head 3 on its side opposite from the support 4 and adapted for movement to enable its cooperating plier carriage 8 to grip a tube disposed over the mandrel rod 5 and mandrel 6 and draw it through the die.

In accordance with the teaching of the invention, a plurality of vertical supports 9 are arranged in a position closely paralleling the longitudinal axis of the tube drawing bench 2, and are each provided with a rotatable roll 10. The rotatable rolls 10 are positioned on the vertical supports 9 in such manner as to be progressively inclined from the die and down the length of the draw chain 7, and are each provided with a helical groove 12. The ends of the roll 10 which are nearest the draw-bench 2 are machined to provide spindles 13, on each of which

a roll 14 is loosely mounted. A motor 15 is disposed relatively adjacent the die head 3 for driving a transmission unit 16 through a coupling 17. The transmission unit 16 drives a shaft 18 through a coupling 19. A worm 20 is mounted on the shaft 18 for each of the rolls 10, which are driven through individual worm gears 21. A stop plate 23 is diagonally disposed between the die head 3 and the first of the adjacent vertical supports 9.

The vertical support 9 which is farthest from the die head 3 is provided with a freely rotating cylinder 24 in lieu of a helically corrugated roll 10.

A support 25 is secured to the tube drawing bench 2 and extends over the die head 3. A shaft 26 is journaled on the support 25 and made to extend therefrom. A grooved roll 27 is secured to the extended end of the shaft 26. A coupling 28 is secured to the other end of the shaft 26 and to the driven element of a transmission unit 29, which is driven from an adjacently disposed motor 30 through a coupling 31. A shaft 32 is journaled on the support 25, above and offset from the shaft 26. The ends of this shaft also extend from the support 25 and one of them carries a link 33 on which there is mounted an idle roll 34. A bell crank lever 39 is secured to the mid-portion of the shaft 32, and connected on one of its ends to a rod 40 which is adapted to slide through an apertured stop 41 on the support 25. A spring 42 is positioned on the free end of the rod 40 and provided with a washer 43 and compression adjusting screw 44, the latter being locked in position by means of a lock nut 45.

A fluid cylinder 46 is secured to the uppermost end of the support 25 and provided with the usual piston rod 47. The piston rod 47 is connected to the other end of the bell crank lever 39, as at 48. A control valve (not shown) is positioned adjacent the die head 3 on its side opposite the motor 30 for actuating the fluid cylinder 46.

An arm 49 is secured to the end of the shaft 32 which is remote from the link 33 and adapted to operate an adjacently mounted switch 50 having a push button 51. The switch 50 actuates the motor 30 through a wiring circuit 52 which is included in a power line 53.

Referring to Figures 5 and 6 of the drawings, a modified form of the invention is disclosed as comprising a plurality of stationary rests 55 which are carried by the vertical supports 9 and made to occupy a common horizontal plane. A

bed 56 is supported by the vertical supports 9 and stationary rests 55, and provided with a plurality of journaled shafts 57 on each of which there is secured a roller 58 and at least one 5 sprocket 59.

A motor 60 is disposed beneath the bed 56 and provided with a coupling 61 through which it drives a transmission unit 62. The driven shaft of the transmission unit 62 is provided with a 10 sprocket 63 which is connected to the various sprockets 59 on the shafts 57 through a chain linkage system, as shown at 64.

In operation, a bundle of tubes, which have been properly prepared for cold drawing, is 15 placed by an overhead crane on the helically grooved rolls 10 and the freely rotatable cylinder 24, which are supported by the vertical supports 9. In this position, the longitudinal axis of the tubes will be at right angles to the axes of the 20 rolls 10, and as the chains or cables of the overhead crane are moved the tubes will spread out along the rolls.

The operator takes a position adjacent the die head 3 of the tube drawing bench and on its 25 side opposite the motor 30, and operates a conveniently disposed switch (not shown) for starting the motor 15, which rotates the rolls 10 in a counterclockwise direction. Regardless of the 30 position of the tubes after they have spread out on the rolls 10, they are caused to move longitudinally until stopped by the guide plate 23, which is adjacent the die head 3. The guide 35 plate prevents their further longitudinal movement except as permitted by the diagonal disposition of its surface, and this allows the helical grooves 12 of the rolls to move the tubes laterally toward the tube drawing bench 2. Due to the progressively inclined axes of the rolls 10, and the diagonal disposition of the guide 40 plate 23, the tubes continue to move until they are relatively adjacent the die head 3. The operator then discontinues the operation of the motor 15, and rolls the tubes by hand onto the grooved roll 27 on the support 25.

The mandrel rod 5 and the mandrel 6 are then 45 placed in the open end of a tube and the valve (not shown) for supplying fluid to the cylinder 46 is operated. This causes the idle roll 34 to hold the tube in close contact with the power 50 actuated roll 27. Simultaneously with the actuation of the fluid cylinder 46, the lever 49, on the shaft 32, will depress the push button 51, of the switch 50, and actuate the motor 30 to rotate the shaft 26 on which the power driven 55 roll 27 is mounted.

As the roll 27 rotates, the tube will be moved over the mandrel and mandrel rod, after which it will fall by gravity down onto the bed of the tube drawing bench 2. The operator then 60 continues the actuation of the fluid cylinder through the valve (not shown) which permits the rod 47 to withdraw the lever 43 and partially rotate the shaft 32. The partial rotation 65 of the shaft 32, in a clockwise direction, permits the push button 51 to assume its extended position and break the circuit to the motor 30.

As the tube being drawn is moved through the die by the chain 7 and plier carriage 8, which 70 grips its pointed end, the operator again actuates the motor 15 through the suitable switch mentioned and thus positions another tube adjacent the idle rollers 14 on the ends of the helically grooved rolls 10, prior to moving it by hand into contact with the grooved roll 27, for 75 succeeding operations.

In the modification disclosed in Figures 5 and 6, the operation is similar to that previously described, except that the tubes are moved by hand across the stationary rests 55 and placed on the power driven rollers 58, which are driven through the chain 64 by the motor 60, which is operated in substantially the same manner as the motor 15 for the helically grooved rolls 10.

In practicing either form of the invention, the 10 operating capacity of a draw-bench is greatly increased, and requires but little effort on the part of a single operator.

While I have shown and described several 15 specific embodiments of my invention, it will be understood that I do not wish to be limited exactly thereto, since various modifications may be made without departing from the scope of my invention, as defined in the following claims.

I claim:

1. In combination with a tube drawing bench, a die, a mandrel rod for supporting a mandrel in the pass of said die, a plurality of helically grooved rolls mounted in progressively higher planes adjacent the chain of said tube drawing bench, the axes of said rolls being at substantial right angles with respect to the longitudinal axis of the bench, a power actuated roll adjacent said die, a movable idle roll mounted above said last named roll, means for moving said idle roll towards said power actuated roll, and means for rotating said first named rolls. 25 30

2. In combination with a tube drawing bench, a die, a mandrel rod for supporting a mandrel in the pass of said die, a stand disposed adjacent the chain of said tube drawing bench, a plurality of helically grooved rolls mounted on said stand in progressively higher planes, the axes of said rolls being at substantial right angles with respect to the longitudinal axis of 40 the bench, a freely rotatable idle roll on the ends of each of said helically grooved rolls which are nearest said tube drawing bench, and means for rotating said helically grooved rolls. 35 40

3. In combination with a tube drawing bench, a die, a mandrel rod for supporting a mandrel in the pass of said die, a stand disposed adjacent the chain of said tube drawing bench, a plurality of helically grooved rolls mounted on 50 said stand in progressively higher planes, the axes of said rolls being at substantial right angles with respect to the longitudinal axis of the bench, a freely rotatable idle roll on the ends of each of said helically grooved rolls which are nearest said tube drawing bench, means for 55 rotating said helically grooved rolls, and a guide plate extending from adjacent said die to the nearest end of said stand.

4. In combination with a tube drawing bench, a die, a mandrel rod for supporting a mandrel in the pass of said die, a stand disposed adjacent the chain of said tube drawing bench, a plurality of helically grooved rolls mounted on 60 said stand in progressively higher planes, the axes of said rolls being at substantial right angles with respect to the longitudinal axis of the bench, in combination with a power actuated roll adjacent said die, a movable idle roll mounted above said last named roll, means for moving said idle roll toward said power actuated roll, and means for rotating said helically grooved 65 70 75 rolls. 70
